KARL HUERTTLE, OF AKRON, OHIO, ASSIGNOR TO LUFTSCHIFFBAU ZEPPELIN GESELLSCHAFT MIT BESCHRAENKTER HAFTUNG, OF FRIEDRICHSHAFEN, BODENSEE, GERMANY.

OUTER COVER OF RIGID AIRSHIPS.

Application filed September 12, 1925, Serial No. 55,804, and in Germany September 18, 1924.

My invention relates to rigid airships and more especially to the outer cover of such ships and the method of manufacturing the same.

- 5 Rigid airships have a hull structure into which the gas bags are inserted and over which the shape giving outer cover is stretched. This outer cover has to sustain considerable stresses resulting from the air 10 pressure and also from the tension occurring while it is being fastened to the hull. On the other hand it should be as light as possible for the purpose of saving useful lift of the airship. Therefore it is necessary to 15 pay special attention to the way of distributing the fabric used and to the method of manufacturing the outer cover.

According to my invention I use a very light and thin fabric for the main middle 20 portions of the individual pieces of the outer cover. The edges of such pieces are reinforced by ribbons or strips of a much heavier and stronger fabric. Points where extraordinary stresses occur may be also reinforced 25 by a superposed layer of an elastic fabric, this elastic fabric having a higher degree of elongation than the main light fabric. This causes a smooth and gradual transition of the stresses from the reinforcement to the 30 main fabric.

The reinforcing fabrics are connected to the main fabric by means of seams sewn by hand or better by a machine. Where there are special reinforcing layers it will be useful to have such seams running in the same direction with that of the stresses. For example at the corners of the individual pieces of the outer cover where such reinforcing layers are very useful, the seams should extend from the corners like rays.

The seams connecting the main portion with the strips at the edges are along and substantially parallel to the edges. For the purpose of providing against a rent and against the possible extension of a rent having occurred it will be advisable to have reinforcing strips at intervals running in cross direction to the edges. Generally it will be sufficient to make such cross strips short but at points of extraordinary stresses on the outer cover it may be useful to have them extending over the full width of the main portion.

It is a further improvement to have the seams not running in straight lines but to

make them curved in a wave-like manner or other suitable form which will cause a better connection and also a better distribution of the stresses.

As it is my aim to provide for an elastic 60 connection it will be useful not to have the threads of the seams knotted at their ends but to let their ends open freely.

The eyelets which are necessary for lacing the individual pieces of the outer cover to 65 the hull or to each other are situated in the edge strips. But, according to my invention, such eyelets are stamped into the edge strip before this strip is sewn to the main fabric. This method is much simpler than the usual 70 way of stamping the eyelets in the finished piece of the outer cover, and it also has the advantage that the light and very sensitive main fabric is treated more carefully. In connection herewith I consider it useful to 75 fold the edge strips so that the eyelets are situated in the double thickness.

Having given a general description of my invention I now want to point it out more in detail referring to the drawings which 80 represent examples embodying my invention.

Fig. 1 is a view on the inside of the outer cover, but partly broken up. Figs. 2 and 3 are cross sections through the edge of an individual piece of outer cover, on an enlarged scale, explaining the method of manufacture. Fig. 4 is the corresponding side view. Figs. 5, 6 and 7 represent other modifications of the connection between main fabric and edge strip.

In Fig. 1 the ends of two pieces of outer cover A and B are shown at their longitudinal edges where they meet and are laced together. Also the corners of the adjacent pieces C, D, E and F are represented.

The main portion of every piece which is made of the light fabric is designated by the letter a, while b is the edge strip into which the eyelets y are stamped. The corners of the pieces are reinforced by special layers c. At those corners the connecting seams d are radially extending from the corner eyelet e. Cross strips f are provided at intervals for the purpose explained above.

In Fig. 3 is shown how the strips b are 105 first folded and provided with a seam l adjacent the edge of each folded portion. Then the eyelets y are stamped in. I prefer to fold the strips b so that legs of unequal length are attained. The main fabric a is 110

put on top of the longer leg of strip *b*, but on its inner side as may be seen from Fig. 3. When it has reached the shorter leg of strip *b* a seam *i* is sewn through *a* and the two legs of *b*. Above this seam fabric *a* is folded backwards so that a new seam *k* may connect the two thicknesses of *a* with the longer leg of *b*.

In Fig. 5 seam *k* catches only one thickness of *a* and connects it with *b*.

In Fig. 6 an additional seam *m* is sewn connecting two thicknesses of *a* with two thicknesses of *b*. This seam *m* is made immediately after *a* has been folded and close to seam *i*.

The example of Fig. 7 corresponds to that of Fig. 6, only seam *k* connects only one thickness of *a* to one thickness of *b*, similarly to the construction shown in Fig. 5.

I do not want to limit myself to the details described or shown in the drawings as many variations will occur to those skilled in the art.

What I claim is:

1. A piece of outer cover for a rigid airship comprising an inner main portion of light fabric and a stronger edge strip surrounding said main portion.

2. A piece of outer cover for a rigid airship comprising an inner main portion of light fabric, and reinforcing layers at the corners of said main portion, the quality of said layers differing from the quality of said main portion.

3. A piece of outer cover for a rigid airship comprising an inner main portion of light fabric and an edge strip of heavier fabric sewn to said main portion, said edge strip being provided with eyelets.

4. A piece of outer cover for a rigid airship comprising an inner main portion of light fabric, and an edge strip of heavier fabric sewn to said main portion, said edge strip being provided with eyelets.

5. A piece of outer cover for a rigid airship comprising an inner main portion of light fabric, an edge strip of heavier fabric, and a seam connecting said two fabrics to each other.

6. A piece of outer cover for a rigid airship comprising an inner main portion of light fabric, and reinforcing layers of fabric at the corners of said main portion, said reinforcing layers being connected to said main portion by seams extending radially from said corners.

7. A piece of outer cover for a rigid airship comprising an inner main portion of light fabric, reinforcing layers of fabric at the corners of said main portion, said reinforcing layers being connected to said main portion by seams extending radially from said corners, the threads of said seams opening freely at their ends without being knotted.

8. A piece of outer cover for a rigid airship comprising an inner main portion of light fabric, an edge strip of heavier fabric sewn to said main portion, and reinforcing strips running inwardly from said edge strip at certain intervals and also sewn to said main portion.

9. A piece of outer cover for a rigid airship comprising an inner main portion of light fabric and reinforcing fabric sewn to said main portion, said reinforcing fabric having a higher degree of elongation than said main fabric.

10. A piece of outer cover for a rigid airship comprising an inner main portion of light fabric, reinforcing fabric sewn to said main fabric by means of seams, the ends of the threads of said seams opening freely without being knotted.

11. A piece of outer cover for a rigid airship comprising an inner main portion of light fabric and an edge strip of another fabric, said second fabric having a higher degree of elongation than said main fabric.

12. A piece of outer cover for a rigid airship comprising an inner main portion of light fabric, and an edge strip of another fabric, said edge strip being folded so as to form two legs of unequal length, said main fabric being also folded but only at its edge, the turned over portion of the main fabric being connected to both legs of the edge strip by means of a common seam, the straight portion of the main fabric and the long leg of the edge strip being connected by a second seam.

13. A piece of outer cover for a rigid airship comprising an inner main portion of light fabric, and an edge strip of another fabric, said edge strip being folded so as to form two legs of unequal length, said main fabric being also folded but only at its edge, the turned over portion of the main fabric being connected to both legs of the edge strip by means of a common seam, the straight portion of the main fabric together with its turned over portion being connected again with both legs of the edge strip by a second common seam, a third seam connecting the straight portions of the main fabric to the long leg of the edge strip.

14. Method of manufacturing pieces of outer cover for rigid airships which consists in sewing a special edge strip of fabric to a main middle portion of lighter fabric, by first folding said edge strip so as to form two legs of unequal length, by then making a longitudinal seam along the folding line, by sewing the edge of said main fabric to both legs of said edge strip by means of a common seam, by turning over said main fabric along said common seam, and by sewing it to the longer leg of said edge strip by means of a third seam.

15. Method of manufacturing pieces of

outer cover for rigid airships which consists in sewing a special edge strip of fabric to a main middle portion of lighter fabric, by first folding said edge strip so as to form 5 two legs of unequal length, by then making a longitudinal seam along the folding line, by sewing the edge of said main fabric to both legs of said edge strip by means of a common seam, by turning over said main fabric along said common seam, by sewing 10 a third seam along said second one thereby connecting the two thicknesses of the main fabric with the two thicknesses of the edge strip, and by making a fourth seam connecting the turned over main portion of said 15 light fabric to the longer leg of said edge strip.

KARL HUERTTLE.
